CLAIM

The ornamental design for a pair of book ends, substantially as shown and described.

DESCRIPTION

FIG. 1 is a perspective view of the pair of bookends showing my new design;

FIG. 2 is an exploded perspective view thereof;

FIG. 3 is a side elevational view taken from the right of FIG. 1;

FIG. 4 is a side elevational view taken from the left of FIG. 1;

FIG. 5 is a front elevational view of FIG. 2;

FIG. 6 is a rear elevational view of FIG. 2;

FIG. 7 is a top plan view of FIG. 2;

FIG. 8 is a bottom plan view of FIG. 2.

The drawings are lined to show simulated denim appearance on the external surfaces of the book ends.
